WILLIAM REINHOLD, OF BUFFALO, NEW YORK

CLIP FOR SUPPORTING STRUCTURAL MEMBERS

Application filed June 4, 1929. Serial No. 368,275.

This invention relates to a clip for temporarily supporting one horizontal structural member from another horizontal structural member and is more particularly intended 5 to be employed in the construction of buildings where the structural members are welded together and wherein it is undesirable to use temporary bolts or the like for supporting the structural members preparatory to welding.

The principal object of this invention is to provide a clip which can be quickly applied to a structural joist and its supporting beam after the joist has been hoisted into position 15 in the usual manner and which clip when applied will reliably hold the joist in proper position for welding to the supporting beam.

A further object is to provide such a clip which can be readily removed after the joist 20 has been welded to its supporting beam, but which cannot become accidentally deranged, which derangement would possibly release the joist temporarily supported and permit it to fall.

Another aim is to provide such a clip which operates to draw the joist flush with the supporting beam in the event that this is not effected when the beam is hoisted into position.

Still further objects are to provide such a clip which is strong and durable, inexpensive in manufacture, and can be used on beams and joists of varying proportions, to reduce shop 30 welding costs and to support the joists in such manner that they can be safely walked on before they are welded without danger of the joists rolling or shaking.

In the accompanying drawings:

Fig. 1 is a perspective view of a joist supported from a supporting beam by a clip embodying my invention.

Fig. 2 is a bottom plan view of the clip shown in Fig. 1.

Fig. 3 is a section taken on line 3—3, Fig.

2 and showing the supporting beam in dotted lines.

Fig. 4 is a vertical section taken on line 4—4, Fig. 2 and showing the joist in dotted lines.

Similar reference numbers refer to like parts in each figure.

The standard construction of steel bearings includes a number of main supporting beams 5 which are connected at their ends to the 55 building columns (not shown) and carry a plurality of joists 6, these joists 6 extending between two of the main supporting beams 5 and being flush with the upper flange of the supporting beam. Considerable difficulty has been encountered in welding such beams together, the principal difficulty being in supporting the joists 6 from the two supporting beams 5 while it is being welded. Heretofore the practice has been to weld some supporting extension to the joists 6 so as to form a shoulder adapted to rest on the supporting beam. This practice, however, increases the shop costs to a point where the advantages, in point of cost, of a welded building, are no 60 65 greater than a riveted construction.

The present invention therefore proposes a removable clip which is applied to the joist and the supporting beam after the joist has been hoisted into position and in general 70 comprises a pair of plates which are adjustably connected so as to be movable toward and from one another and are adapted to engage the upper surfaces of the upper flanges 75 of the supporting beam and joist, these plates 80 carrying a plurality of hook bolts which engage the under faces of the upper flanges of both the supporting beam and the joist.

These supporting plates 7 and 8 are each 85 preferably of rectangular form and are of such size and proportions as to support the joist 6. On the under side of each plate adjacent its outer side and spaced a distance from one end is welded a block or shoulder 9. In line with this block or shoulder 9 each 90

of the plates is provided with a pair of openings 10, these openings receiving hook bolts 11. Each of these hook bolts 11 comprises a vertical shank 12 which extends up through 5 the opening 10 in the plates 7 and 8 and is threaded to receive a nut 13 and a lower curved part 14, the horizontal outer end 15 of which is adapted to engage and dig into the under side of the upper flange of the joist 6 when the nut 13 is screwed down against the plate. Each of these hook bolts is preferably made of a hardened metal and the end 15 is recessed as indicated at 16 and the rim of this recess sharpened so as to insure a 15 secure engagement of this end with the joist 6.

A similar hook bolt 17 is provided for each plate, this hook bolt 17 extending through the block or shoulder 9 and its lower end being adapted to bite into the under side of 20 the flange of the supporting beam in the same manner as the hook bolts 11.

The plates 7 and 8 are arranged at opposite sides of the joist 6 and for the purpose of holding these plates together and still permit of the same to be adjustably moved toward and from one another to adapt the clip to joists of varying widths a link 18 is provided, this link being made of a suitable length and having longitudinal slots 19 at its 30 opposite ends. One of the slots 19 receives the shank of the central hook bolt 11 carried by the plate 7 and the other slot receives the shank of the central hook bolt 11 of the plate 8, the nuts of these hook bolts bearing against 35 the upper sides of the link. It is therefore apparent that when the clips are free the link 18 holds the two clips together, but in no way interferes with the application of the clips to a beam and joist, the hook bolts being 40 drawn into place in the same manner as though the link 18 were not provided.

In applying the clip as described the joist 6 is first hoisted into proper position relative to its supporting beam 5. The plates 7 and 8 are then laid on the joist 6 and supporting beam 5 in such manner that the hook bolts can be swung under the upper flanges of these structural members. The plates 7 and 8 are then moved together and arranged so 50 that the blocks or shoulders 9 bear against the edge of the upper flange of the supporting beam 5, as shown in Fig. 1, and also bear against the opposite edges of the upper flange of the joist 6. By means of this block or shoulder 9 the plates are properly positioned and the hook bolts 11 are swung into proper position to engage the under sides of the upper flanges of the joist 6 and the hook bolts 17 and swung into proper position to 55 engage the under side of the upper flange of the supporting beam 5. The nuts of the hook bolts are then tightened up so as to draw the curved ends of each hook bolt into firm engagement with the under sides of the upper flanges of the structural members, the sharp-

ened ends of these hook bolts insuring a reliable engagement. The joist 6 so supported can then be welded and the clip thereafter removed by loosening the nuts of the hook bolts so as to release the hook bolts from their engagement with the structural members and also to permit of the plates 7 and 8 being separated.

From the foregoing it is apparent that the present invention provides a very simple, light and inexpensive clip for supporting one horizontal structural member from another which when applied is securely attached to both and cannot become accidentally deranged. The clip is also very easily applied and removed and by the provision of the shoulder or block 9 is readily placed in its proper position without particular care on the part of the workman. Both parts of the clip are also held together but are adjustably movable toward and from one another to adapt the clip to joists of varying widths, this adjustment, however, requiring no operations on the part of the person applying or removing the clip. It will also be noted that this clip draws the joist 6 flush with the upper surface of the supporting beam 5 and therefore insures the proper vertical positioning of the joist relative to the supporting beam.

I claim as my invention:

1. A clip for supporting one horizontal structural member from another horizontal structural member, comprising a plate adapted to overlay a part of each of said structural members, a shoulder projecting downwardly from said plate and adapted to engage each of said structural members at the corner formed between them and thereby position the plate with reference to said structural members, and means carried by said plate for engaging a surface of said supported structural member.

2. A clip for supporting one horizontal structural member from another horizontal structural member, comprising a pair of members adapted to overlay the opposite sides of said supported structural member and also the adjacent parts of said supporting structural member, means carried by each of said last named members for engaging an under surface of said supported structural member and means connecting said last named members but permitting their movement toward and from one another, comprising an independent slotted link secured to one of said members, and a headed projection provided on the other member, said slot receiving the shank of said headed member.

3. A clip for supporting one horizontal structural member from another horizontal structural member, comprising a pair of plates each adapted to overlay one side of said supported structural member and also

the adjacent parts of said supporting structural member, a plurality of screw fastenings carried by each of said plates and arranged to engage each of said structural members and means connecting said plates comprising an independent link having at least one longitudinal slot, said slot receiving the shanks of one screw fastening of each plate whereby said plates are movable toward and from one another.

In testimony whereof I hereby affix my signature.

WILLIAM REINHOLD.
